A. Conwell,

Tanning Hides

Patented Nov. 4, 1831.

Abraham Bonwell.

Letters Patent. No. 4.1621.

The Schedule referred to in these Letters Patent, and making part of the same, containing a description in the words of the said, Abraham Bonwell himself, of his Improvement in the Tan Yard.

Be it known, that I, Abraham Bonwell, of the Town of Lowell, in the County of Fayette, and State of Indiana, have invented a new and useful improvement in Tanning leather, and that the following is a full and exact description of the construction and operation of the Tan Yard as improved by me.

Figures A, numbered 1, 2, 3, 4, &c. represent rats of the ordinary size, placed at the common distance apart, but which may be placed at any distance apart to suit the convenience or pleasure of the constructor.

Figure B, is a pipe or conductor placed on a level with the bottom of the rats equidistant between the rows of rats and passing through the conductor reservoir, &c.

Figure C, represents a reservoir or cistern through which the conductor B, passes, and should be located at the centre of the conductor, and be made so deep below the bottom of the rats as to be capable of receiving at least the contents of one rat upon the upper opening of the pipe. The reservoir reservoir, may however, be dispensed with by placing a pump in the centre of the conductor B, and inserting the conductor into the pump on each side as represented in the dotted line in the drawing.

Figures d, represent pipes which communicate with the rats and the conductor B, and are inserted at the bottom of the rat level with the conductor.

Figures e, represent cocks or spigots which stop the pipes d, and must be long enough so as to extend from their insertion in the pipes to the top or near the top of the rats so as to be turned without descending into the rats.

Figures f, represent strainers or (as they are denominately termed) letch eyes, and are formed by placing an inch plank twelve inches or less wide upright extending from the bottom to the top of the rats in the angle, and filled with small holes.

18247

Figure 16 represents a pump which is necessary in case the cistern is used.
Figure 17 represents a cock in the center of the conductor B, and has a spigot extending to the top of the cistern and is used in drawing the liquor or ore from the cistern into the cistern.

(The advantages to be derived from this invention are first, the ease and facility by which ore or liquor can be changed from one vat to another, as for instance, should it be required to conduct the ore from vat A, which is full, into vat B, which is empty or simply filled with dry bark, it is only necessary to turn the spigots in each of these vats, and one half of the ore or liquor will be through the conductor conveyed into this at A. V. T. then by stopping the cock in A. V. T. and opening the cock in B. in the conductor, the balance of the ore will be deposited in the cistern (if one be used) and can be raised by the pump and conveyed by pipes or hose into A. V. T. secondly, that at any time when ore in any vat becomes too weak to suit the heds it can be drawn off and its place be supplied by stronger ore, without the labor more necessary in removing the heds.

(Thirdly, that weak ore can be drawn off and fresh and stronger applied without removing or disturbing the heds. Fourthly, that it leaves the bark in such a condition in the vats, that all its strength can be retained and the tan left perfectly drained and easy of removal. Fifthly, that the tanning leather will be much facilitated because ore of any strength can be applied to heds, so as to stay in their tanning. Sixthly, that much labor now used in tanning, will be saved because the ore or liquor is changed and applied at pleasure without raising the heds or disturbing them.

The inventor claims as new in the annexed drawing and description of his improved Tanyard, the application of the conductor and pipe to the vat as above shown and specified, by the means of which much labor and bark in the business of tanning is saved because the ore or liquor is changed and applied at pleasure without raising the heds or disturbing them.
